Bernard E. Curran, Sewickley, Pa., assignor to H. H. Robertson Company, Pittsburgh, Pa., a corporation of Pennsylvania

Application December 4, 1956, Serial No. 626,140

7 Claims. (Cl. 98—31)

This invention relates to a building and air distributing structure and more particularly to a building and air conditioning structure of the type forming the subject matter of United States patent to R. P. Goemann, No. 2,729,429, dated January 3, 1956.

The Goemann patent discloses a building and air conditioning and distributing system and apparatus wherein cellular metal floors form the load supporting structure at each of selected stories of a multi-story building, and the present invention has for an object to provide novel apparatus for conducting air from one or more of the air conducting floor cells to an outlet or discharge unit.

A further object of the invention is to provide novel connecting apparatus which may be used with advantage in connecting an outlet or discharge unit to an air conducting cell of a multicellular floor which includes provision for temporarily supporting and adjusting a screed box in surrounding relation to the outlet connecting apparatus during the pouring of a cementitious floor fill over the multicellular load supporting floor.

With these general objects in view and such others as may hereinafter appear the invention consists in the outlet connecting apparatus for the purpose described and in the various structures, arrangements and combinations hereinafter described and particularly defined in the claims at the end of this specification.

In the drawings illustrating the preferred embodiment of the invention:

Fig. 1 is a diagrammatic plan view of a portion of a cellular metal floor wherein air is conducted through selected floor cells as shown in said Goemann patent above referred to;

Fig. 2 is a cross sectional view on line 2—2 of Fig. 1 viewed in the direction of the arrows;

Fig. 3 is a vertical sectional detail view showing the preferred form of outlet connecting apparatus erected upon the upper surface of an air conducting cell of a multicellular floor and showing the apparatus for temporarily supporting a screed box above the cell;

Fig. 3A is a cross sectional detail view of a temporary fastening, to be described;

Fig. 4 is a similar view showing the temporary screed box supporting apparatus removed and replaced by an air discharge outlet connection;

Fig. 5 is a perspective detail view of the screed box;

Fig. 6 is an exploded perspective view of the components of the outlet connecting and screed box supporting apparatus shown in Fig. 3;

Fig. 7 is a plan view of the screed box and illustrating a modified form of the outlet connecting apparatus;

Fig. 8 is a vertical sectional detail similar to Fig. 3 illustrating a slightly modified form of the outlet connecting and screed box supporting apparatus;

Fig. 9 is a perspective detail view of a cover member for the screed box;

Fig. 10 is a vertical sectional view of the outlet connecting and screed box supporting apparatus applied to

2

a structure wherein an air conducting conduit is extended through a non-air conducting portion of the cellular floor; and

Fig. 11 is a similar view of a different structure of air conducting conduit extended through a non-air conducting portion of the cellular floor.

The building and air conditioning and distributing structure forming the subject matter of the Goemann patent above referred to embodies a cellular metal floor of the type illustrated in the patent to Young, No. 1,867,433, and wherein a multiplicity of air conducting cells form a part of the structural load supporting cellular metal floor itself. As illustrated in the Goemann patent, provision is made for supplying air, particularly conditioned air, to selected and a number of spaced air conducting floor cells, and the present invention is particularly concerned with novel connecting means or apparatus which may be used with advantage in making the connection between one or more of the air conducting cells to outlets disposed above or below a cellular metallic floor. In the various forms of the connecting means, herein illustrated, provision is made for simplifying the labor involved in field erection of the components and for facilitating the manufacture of the various components in the plant.

Referring now to the drawings, as shown in Figs. 2, 3 and 4, the connecting apparatus is illustrated as mounted upon an air conducting cell 10 of a multicellular metal floor and air distributing structure in a building of the type illustrated in the Goemann patent above referred to. The air conducting cell 10 is provided with an opening 11 in the upper wall thereof, and the outlet connecting apparatus is mounted upon the cell and in registry with the opening in the manner illustrated in Figs. 2 and 4.

In one form of the invention the outlet connecting apparatus indicated generally at 16 may comprise a pair of similarly shaped hollow shoe members 24, 26, each having a peripheral outwardly projecting flange 25, 27 on their lower ends arranged to embrace the edges of the upper wall defining the opening 11. The hollow shoe members 24, 26 are shaped to enable the upper shoe 24 to nest over the lower shoe 26 and when erected to dispose the peripheral flange 27 of the lower shoe 26 within the air conducting cell 10 and against the portion of the wall surrounding the opening 11 and to dispose the peripheral flange 25 of the upper shoe 24 in airtight relation to the corresponding outer surface of the upper wall of the cell, a gasket 29 being provided between the flange 25 and said upper surface. The upper ends of the shoe members 24, 26 are provided with inwardly projecting flanges 31, 33 provided with openings for the reception of fastening members so that when the upper flanges are pulled together, the lower flanges 26, 27 will be clamped into engagement with the upper wall of the cell. In practice the upper and lower shoe members 24, 26 may be temporarily secured in assembled relation to the opening 11 by flat head screws 70 extended through clearance openings 71, 72 in the flanges 31, 33 and by cooperating nuts 74, as indicated in detail in Fig. 3A, the nuts comprising a commercially available quick fastening type known as "Tinnerman" nuts.

In accordance with the present invention the connecting apparatus is arranged to cooperate with a substantially rectangular screed box 12 having an inwardly extended bottom flange 13 and outwardly extended top flanges 15, the box being embedded in the concrete floor fill 14 above the air conditioning cell 10 and in surrounding relation to the air distributing outlet structure 16, novel provision being made for initially supporting and adjusting the screed box 12 relative to the outlet connecting structure

to present the top flanges 15 of the box slightly below the screed line so that when a cover member 42 is assembled therewith prior to the pouring operation the upper surface of the cover member will be level with the screed line of the subsequently poured concrete fill. As shown in Fig. 3, a screed box supporting and levelling shoe 21 having an upper outwardly extended flange 22 is therein shown as temporarily connected to the shoe clamping members 24, 26 through upper flanges 31, 33 by screws 28, the screws extending through clearance openings in member 21 and flange 31 and cooperating with threaded openings in flange 33. The levelling shoe 21 is inverted relative to the adjacent shoe 24 and may be provided with a closed bottom wall 30. As herein shown, one set of levelling screws 32 extends through the flange 22 of member 21 and into threaded openings 34 in the flange 13 of the screed box so as to permit raising or lowering of the box relative to the outlet connecting structure and to level the top of the box parallel with and slightly below the screed line of the subsequently poured concrete fill. A second set of screws 36 extends through threaded openings 37 in the shoe member 21 and engage the upper surface of the screed box flange 13 to effect levelling of the box laterally and angularly and to lock the box in its adjusted position. After pouring and hardening of the concrete floor fill the temporary supporting and levelling shoe 21 may be removed. The screws 70, together with nut 74, retain the shoe clamping members 24, 26 in assembled relation when the screws 28 are removed, and a stack member 18 forming part of the air distributing outlet box 19 may be directly connected to the top of the shoe member 24 by the screws 28, as shown in Fig. 4, a suitable gasket 38 being interposed between the stack flange and the member 24.

As shown in plan in Fig. 7, in a modified form of levelling member 21 the continuous upper flange may be eliminated and the member 21 may instead be provided with laterally extended ears 40 for receiving the levelling and locking screws 32, 36. Fig. 8 illustrates a further modification wherein the side walls of the shoe clamping members 24, 26 and the levelling member 21 are vertical rather than tapered as in Fig. 3. In practice after the levelling operation the screed box may be provided with a cover member 42, as shown in Fig. 9, to prevent entrance of concrete during the floor fill operation, the cover being secured by flat head screws 75 engages with threaded openings in the flanges 15.

Figs. 10 and 11 illustrate the screed box 12 and levelling structure in operative relation to duct elements 44, 46 respectively extended through the underside of the flooring wherein air may be conducted from one or more of the air conducting cells from the underside thereof to an outlet unit laterally spaced from the air conducting cells and mounted upon the upper side of the floor. In Fig. 10 the inverted levelling member or shoe 21 is connected by the screws 28 to the shoe member 48 of the duct structure 44 and is provided with levelling screws 32 and locking screws 36. Fig. 11 shows the outlet connecting structure and the levelling member 21 as having straight side walls, the levelling and locking screws 32, 36 cooperating with the screed box as above described.

The structure shown in Fig. 10 includes the duct member 44 extended through an opening in a non-air conducting cell 9 of the multicellular flooring and is provided with outwardly extended upper flanges 49 arranged to rest upon a bridge member 50 extended across adjacent cells of the floor. The lower end of the duct member 44 is provided with inwardly extended flanges 52 provided with openings adapted for the reception of fastening members 54 by which an inverted flanged shoe member 56 may be secured. The shoe member 56 is adapted for connection to an air supply conduit, not shown, extended transversely of the cells in the multicellular flooring and connected at its other end in communication with one of the air conducting cells. A sealing gasket 58 may

be provided between the lower flange 52 and the upper flange of the shoe member 56. The outlet connecting structure indicated generally at 20 includes an upper shoe member 48 which is provided with an outwardly extended lower flange 60 and an inwardly extended upper flange 62 to which the inverted supporting and levelling member 21 is connected by the screws 28. In practice the supporting and levelling member 21 may be removed upon hardening of the concrete floor fill 14 and replaced by an outlet structure of the type shown in Figs. 2 and 4.

In the modified form illustrated in Fig. 11 the connecting duct structure 46 is extended through the non-air conducting cell portion 9 of the multicellular floor and is provided with an outwardly extended lower flange 47 at its lower end for connection to an air conducting conduit, not shown, extended from the underside of laterally spaced air conducting cell of the multicellular floor. The upper end of the duct member 46 is provided with inwardly extended flanges 45 which may be connected by screws 51 to the inwardly extended flanges 53 of a shoe member 55 having outwardly extended flanges 56 at its lower end resting on the bridge member 50 extended between adjacent cells of the non-air conducting cellular portion of the multicellular flooring. A gasket 65 may be provided between the flanges 53, 45 to provide an airtight connection. In practice the supporting and levelling member 21 shown in Fig. 11 may likewise be removed upon hardening of the floor fill 14 and replaced by an outlet box structure as above described.

While the preferred embodiments of the invention have been illustrated and described, it will be understood that the invention may be embodied in other forms within the scope of the following claims.

Having thus described the invention, what is claimed is:

1. In an air distributing and building structure, a cellular metal load supporting floor having an opening in the upper wall thereof and flanged outlet connecting means including an upright hollow rectangular shoe member communicating with said opening and supported by said upper wall and having side walls, an outwardly extended bottom flange and an inwardly extended top flange extended above said opening, a substantially rectangular screed box having side walls and an inwardly extended bottom flange and means for temporarily supporting and adjusting said screed box vertically and angularly with relation to said outlet connecting means to vary the height and level thereof including an inverted rectangular shoe member having side walls and a closed lower wall and detachably secured to said inwardly extended upright shoe flange, said inverted shoe member having an outwardly extended flange at its upper end, a set of screws extended through said outwardly extended inverted shoe flange and threadedly engaged with the bottom flange of said screed box, and a second set of screws threaded through said outwardly extended inverted shoe flange and having their lower ends resting on top of said screed box flange, said temporary supporting and adjusting means being adapted for subsequent removal upon pouring and hardening of a concrete floor fill over said cellular metal floor to be replaced by an air distributing outlet unit.

2. An air distributing structure as defined in claim 1 wherein the outlet connecting means is connected in direct communication with an air carrying cell of said cellular metal floor.

3. An air distributing structure as defined in claim 1 wherein the screed box is provided with a cover to prevent entrance of concrete during the floor fill operation.

4. An air distributing structure as defined in claim 3 wherein the screed box is provided with outwardly extended upper flanges, and wherein the cover member comprises a flat sheet detachably connected to said screed box flanges.

5. In an air distributing and building structure, a cellular metal load supporting floor having an air conducting

cell forming a component of the floor, said cell having an opening in the upper wall thereof, outlet connecting apparatus comprising an upper upright hollow rectangular shoe member and a lower upright hollow rectangular shoe member each having side walls and outwardly extended bottom flanges arranged to embrace the inner and outer surfaces of the upper wall portions defining said opening, the upper of said shoe members being relatively larger and arranged in substantially nesting relation with the lower shoe member, each of said upright shoe members being also provided with inwardly extended upper flanges adapted to be secured together in spaced relation to effect clamping of said lower flanges about said opening, a substantially rectangular screed box having side walls and an inwardly extended bottom flange, and means for temporarily supporting and adjusting said screed box vertically and angularly with relation to said outlet connecting means to vary the height and level thereof including an inverted rectangular shoe member having side walls and a closed lower wall and detachably secured to said inwardly extended flanges of said upright shoe members, said inverted shoe member having an outwardly extended flange at its upper end, a set of screws extended through said outwardly extended flange and threadedly engaged with the bottom flange of said screed box, and a second set of screws threaded through said outwardly extended flange and having their lower ends resting on top of said screed box flange, said temporary supporting and adjusting means being adapted for subsequent removal upon pouring and hardening of a concrete floor fill over said cellular metal floor to be replaced by an air distributing outlet unit.

6. In an air distributing and building structure, a cellular metal load supporting floor, a connecting air carrying conduit structure including a portion extending upwardly through an opening in a non-air carrying cellular portion of the floor, outlet connecting means including a hollow upright rectangular shoe member supported by said floor and in communication with said air carrying conduit, said hollow shoe member having side walls, an outwardly extended bottom flange and an inwardly extended top flange disposed above the floor opening, a substantially rectangular hollow screed box disposed above said outlet connecting means and having side walls of an inwardly extended bottom flange, and means for temporar-

ily supporting and adjusting said screed box vertically and angularly with relation to said outlet connecting means to vary the height and level thereof including an inverted rectangular shoe member having side walls and a closed lower wall and detachably secured to said inwardly extended upper shoe flange, said inverted shoe member having an outwardly extended flange at its upper end, a set of screws extended through said outwardly extended upper flange and threadedly engaged with the bottom flange of said screed box, and a second set of screws threaded through said outwardly extended upper flange and having their lower ends resting on top of said screed box flange, said temporary supporting and adjusting means being adapted for subsequent removal upon pouring and hardening of a concrete floor fill over said cellular metal floor to be replaced by an air distributing outlet unit.

7. In an air distributing and building structure, a cellular metal load supporting floor having an air conducting cell forming a component of the floor, said cell having an opening in the upper wall thereof, outlet connecting apparatus comprising an upper upright hollow shoe member and a lower upright hollow shoe member each shoe member being rectangular and having side walls and outwardly extended bottom flanges arranged to embrace the inner and outer surfaces of the upper wall portions defining said opening, the upper of said shoe members being larger and arranged in substantially nesting relation with the lower shoe member, said shoe members being also provided with inwardly extended upper flanges adapted to be secured together to effect clamping of said lower flanges about said opening, separate fastening means connecting said inwardly extended flanges for temporarily retaining said shoe members in assembled relation about said opening, a substantially rectangular hollow screed box, disposed above said outlet connecting apparatus and means temporarily supported by said shoe members for supporting and adjusting said screed box vertically and angularly with relation to said outlet connecting apparatus to vary the height and level thereof, said temporary supporting and adjusting means being adapted for subsequent removal upon pouring and hardening of a floor fill over said cellular floor to be replaced by an air distributing outlet unit.
